UNITED STATES PATENT OFFICE.

AUGUST SWEDBERG, OF KINGSTON, PENNSYLVANIA, ASSIGNOR TO SWEDBERG MFG. CO., OF WILKES-BARRE, PENNSYLVANIA, A CORPORATION OF PENNSYLVANIA.

WINDOW-SCREEN.

1,242,072.

Specification of Letters Patent.

Patented Oct. 2, 1917.

Application filed March 12, 1917. Serial No. 154,254.

To all whom it may concern:

Be it known that I, AUGUST SWEDBERG, a citizen of the United States, residing at Kingston, in the county of Luzerne and

5 State of Pennsylvania, have invented certain new and useful Improvements in Window-Screens, of which the following is a specification, reference being had to the accompanying drawings.

10 This invention relates to certain improvements in window screens and has relation more particularly to a device of this general character of a roller type; and it is an object of the invention to provide a screen of 15 this general character having novel and improved means whereby the same may be readily unwound in accordance with the height to which a window may be raised together with means whereby the screen may 20 be automatically wound upon the lowering of the window.

A further object of the invention is to provide a novel and improved device of this general character including a spring roller 25 with which the screen is operatively engaged and wherein the screen when extended or unwound is relieved from the tension of the roller.

A still further object of the invention is 30 to provide a novel and improved device of this general character wherein the supporting parts for the screen are capable of longitudinal adjustment so that the same may be readily applied within window frames or 35 other openings of different widths.

Furthermore it is an object of the invention to provide a novel and improved device of this general character including a member adapted to support a roller with 40 which the screening element is operatively engaged together with a shield or apron carried by said member and coacting with the roller or the screening element wound therearound for preventing the passage of 45 insects or the like through the open space afforded by the roller.

It is also an object of the invention to provide a device of this general character including a supporting member and a 50 spring-operated roller engaged with said member together with coacting means carried by the supporting member and the roller for normally holding the roller against movement under the influence of its spring, and wherein a portion of said co-

acting means is adapted to be manually operated to release the roller so that the same may be caused to automatically wind the screening element.

The invention consists in the details of 60 construction and in the combination and arrangement of the several parts of my improved screen whereby certain important advantages are attained and the device is rendered simpler, less expensive and otherwise more convenient and advantageous for use, all as will be hereinafter more fully set forth.

The novel features of the invention will 70 hereinafter be definitely claimed.

In order that my invention may be the better understood, I will now proceed to describe the same with reference to the accompanying drawings, wherein—

Figure 1 is a view in elevation illustrating 75 a window screen constructed in accordance with an embodiment of my invention and in applied position;

Fig. 2 is a vertical sectional view taken through the structure as shown in Fig. 1, 80 the screen fabric being indicated diagrammatically.

Fig. 3 is a view in top plan of the supporting 85 member and its concomitant parts as herein embodied;

Fig. 4 is a longitudinal vertical sectional view taken through Fig. 3;

Fig. 5 is a view in end elevation with a portion broken away of the supporting member as herein set forth;

Fig. 6 is a sectional view taken substantially on the line 6—6 of Fig. 4;

Fig. 7 is a view partly in section and partly in elevation of the end portion of the supporting member opposite to that shown 95 in Fig. 6;

Fig. 8 is a view in end elevation of the roller as herein included;

Fig. 9 is a view in elevation with a portion broken away of the rod adapted to be 100 secured to the window sash;

Fig. 10 is an enlarged sectional view taken substantially on the line 10—10 of Fig. 4;

Fig. 11 is a view partly in elevation and partly in section of the supporting member 105 as herein embodied, the coacting roller being omitted;

Fig. 12 is a sectional view taken substantially on the line 12—12 of Fig. 11;

Fig. 13 is a fragmentary view in perspec-

tive of the apron or guard as herein embodied; and

Fig. 14 is a fragmentary view in perspective of the end portion of the supporting member opposite to that shown in Fig. 11.

As disclosed in the accompanying drawings, S denotes a supporting member herein disclosed as comprising two elongated flat plates 1 of substantially the same length, 10 and one of said plates has its opposite longitudinal marginal portions returned to afford guideways 2 with which the second plate is slidably engaged. By this arrangement it will be at once self-evident that the supporting member S may be readily and conveniently adjusted in order to compensate for window frames or other openings of different widths.

The outer ends of each of the sections or 20 plates 1 of the supporting member S are provided with the upstanding extension 3. In practice the supporting member S is adapted to be rested upon the sill of a window frame or the lower wall of a window 25 opening with the upstanding portions 3 in contact with the vertical walls of the frame or opening and in order to anchor the member S in such position the upstanding portions 3 are provided with the openings 4 30 through which suitably fastening means are adapted to be directed.

R denotes a roller also comprising two sections 5 and 6 adjustably engaged one with the other so that said pole may be 35 lengthened or shortened in accordance with the necessities of practice.

As herein disclosed, each of the sections 5 and 6 is tubular and the outer end of the section 5 has inserted therein the block 7 40 keyed or otherwise secured, as at 8, within said section 5. The outer face of the block 7 is arranged slightly inward of the adjacent or outer end of the section 5 and has extending outwardly therefrom at its axial 45 center the cylindrical sleeve 9 which terminates substantially flush with the adjacent or outer end of the section 5. The outer end of the section 5 is provided with the inwardly directed annular flange 10 having 50 produced in its free or inner marginal portion the ratchet teeth 11 for a purpose to be hereinafter more particularly set forth. The section 5 is also provided with a longitudinally disposed slot 12 extending substantially the entire length thereof for a 55 purpose to be hereinafter decided.

The section 6 is adapted to be telescopically engaged within the section 5 and the inner end portion of said section 6 is provided with a threaded opening 14 adapted 60 to be engaged by the binding screw 15 also disposed through the slot 12 whereby it will be perceived that the sections 5 and 6 may be readily and effectively held at their different relative adjustments.

Permanently secured within the section 6 at a point slightly inward of the outer end of said section is a head 16 and which is in swiveled engagement therewith the elongated rod 17 extending inwardly of the section 6. The portion of the rod 17 in advance of the head 16 is flattened, as indicated at 18, and terminates inwardly of or substantially flush with the outer end of the section 6. The outer end of the section 6 is 75 also defined by an inwardly directed annular flange 19 resulting in a restricted opening 20 whereby operative engagement may be had with the flattened portion 18 in a manner and for a purpose which will be hereinafter 80 set forth.

The inner end portion of the rod 17 is rotatably disposed through the block or head 21 fixed within the section 6 and which serves to maintain the rod 17 disposed axially of the section 6. 85

Coacting with the rod 17 in a conventional manner is the coil spring 22 which serves to impose the requisite tension upon the roller R as to cause the same to automatically rotate in one direction. 90

One of the extensions 3 of the supporting member S is provided with an inwardly directed pin 23 which is adapted to be received by the cylindrical sleeve 9 of the section 5, 95 and whereby said end portion of the roller R is rotatably supported. The second extension 3 is provided with the inwardly directed sleeve 24 angular in cross section and adapted to receive the flattened end portion 18 of the rod 17. By having the sleeve 9 and flattened portion 18 hereinbefore referred to substantially confined within their respective sections 5 and 6, it will be at once self-evident that the outer ends of said sections will be substantially in contact with the extensions 3, the advantages of which being, it is thought, clearly apparent to those skilled in the art to which my invention appertains. 105

The first named extension 3 is provided with an elongated slot 25 positioned inwardly of the pin 23 carried by said extension, and disposed through said slot 25 is the inwardly directed finger 26 carried by the inner end portion of the arm 27 extending substantially transversely of the extension 3 and overlying the outer face thereof. The arm 27 is pivotally mounted intermediate its length, as at 28, with said extension 3 and the outer portion of said arm is returned, as at 29, to afford convenient means whereby rocking movement may be imparted to the arm 27 as may be necessitated by the requirements of practice. 115

The finger 26 is adapted to be maintained in operative engagement with a ratchet tooth 11 through the medium of the spring 30 herein disclosed as anchored at one end to the extension 3 and having its opposite or 120

free end contacting with an edge of the arm 27 at a point intermediate the slot 25 and the pivot 28. The edge of the arm 27 with which the free end of the spring 30 coacts 5 is provided with a longitudinally disposed groove 31 whereby said free end portion of the spring 30 is maintained in requisite contact with the arm. It is thought to be self-evident that when it is desired to have the 10 roller R rotate under the influence of the spring 22, it is only necessary to manually move the returned portion 29 in a direction to cause the finger 26 to move toward the pin 23.

15 The sections 5 and 6 of the roller R are each provided with a plurality of longitudinally spaced prongs or fingers 32 with which an end portion of a screen fabric F is adapted to be engaged so that said screen 20 fabric is conveniently and effectively secured to the roller. The opposite or outer end portion of the fabric F has operatively engaged therewith the pole or rod P. This pole or rod P also comprises longitudinally 25 adjustable sections 33 and herein disclosed as in telescoping relation. The outer ends of the sections 33 are provided with the heads 34 adapted to frictionally engage the side or vertical portions of a window frame 30 or other opening.

The pole or rod P is also adapted to be secured to a horizontal rail of a sash so that when the sash is adjusted into an open position the screen fabric F will be unwound 35 from the roller R in order to prevent passage of insects through the open window. When the sash is to be adjusted into closed position it is only necessary to impart the requisite movement to the arm 27 to permit 40 the screen fabric F to be automatically wound upon the roller R. It is also to be particularly noted that as the finger 26 is normally in engagement with a ratchet tooth 11 the screen fabric F is relieved of 45 strain or pull thereon when unwound by the spring 22 of the roller R.

When the roller R is in applied position the same is slightly separated from the plates 1 thereof and in order to prevent the 50 ingress of insects, dust or the like through said space I find it of advantage to provide the apron or shield A which is adapted to be interposed between the extensions 3.

As herein embodied, the apron or shield 55 A comprises two elongated plates 35 slidably engaged one with the other so that said apron or shield A may be readily adjusted in accordance with the necessities of practice. A longitudinal marginal portion of 60 each of the plates 35 of the apron at the outer end thereof is provided with a barrel 36 or the like which is adapted to receive the inwardly directed pins 37 carried by the extensions 3 adjacent an inner corner thereof. 65 By this arrangement it will be at once self-

evident that the apron or shield A is mounted for swinging movement so that the outer marginal portion thereof may contact with the roller R or the fabric F wound there-around.

It is also preferred that the plates 35 of the apron or shield A be concavo-convex in cross section so that the apron or shield may be readily and effectively applied. It is also to be noted that the apron or shield A 75 is so positioned relative to the roller R as not to interfere or obstruct the winding of the fabric F upon the roller R.

From the foregoing description, it is thought to be obvious that a screen constructed in accordance with my invention is of an extremely simple and comparatively inexpensive nature and is particularly well adapted for use by reason of the convenience and facility with which it may be assembled, 80 and it will also be obvious that my invention is susceptible of some change and modification without material departure from the principles and spirit thereof and for this reason I do not wish to be understood as 85 limiting myself to the precise arrangement and formation of the several parts herein shown in carrying out my invention in practice, except as hereinafter claimed.

I claim:

1. A device of the character described comprising a supporting member provided with lateral extensions, a roller rotatably supported by said extensions, one end portion of the roller being provided with a ratchet wheel, an arm pivotally engaged with the outer face of the extension of the supporting member adjacent the end of the roller provided with the ratchet wheel, said arm normally coacting with the ratchet 100 wheel for holding the roller against movement in one direction, said extension being provided with an opening through which a terminal of the arm extends to engage the ratchet wheel, the outer end portion of the 105 arm being laterally disposed in a direction inwardly of the supporting member to afford engaging means.

2. A device of the character described comprising a supporting member provided 115 with lateral extensions, a roller rotatably supported by said extensions, one end portion of the roller being provided with a ratchet wheel, an arm pivotally engaged with the outer face of the extension of the 120 supporting member adjacent the end of the roller provided with the ratchet wheel, said extension being provided with an opening through which a terminal of the arm extends to engage the ratchet wheel, an elongated 125 spring anchored at one end to the outer face of said extension and having its opposite end portion bearing against an edge of the arm for normally maintaining the arm operatively engaged with the ratchet wheel of 130

the roller for holding the roller against movement in one direction.

3. A device of the character described comprising a supporting member provided with lateral extensions, a roller rotatably supported by said extensions, one end portion of the roller being provided with a ratchet wheel, an arm pivotally engaged with the outer face of the extension of the supporting member adjacent the end of the roller provided with teeth, said extension being provided with an opening through which a terminal of the arm extends to engage the ratchet wheel, an elongated spring anchored at one end to the outer face of said extension and having its opposite end portion bearing

against an edge of the arm for normally maintaining the arm operatively engaged with the ratchet wheel of the roller for holding the roller against movement in one direction, the edge of the arm with which the free end of the spring coacts being provided with a longitudinally disposed groove whereby said free end portion of the spring is maintained in requisite position with the arm.

In testimony whereof I hereunto affix my signature in the presence of two witnesses.

AUGUST SWEDBERG.
